HEEL-BREASTING MACHINE

Bernard T. Leveque, Wenham, Mass., assignor to
United Shoe Machinery Corporation, Flemington, N. J., a corporation of New Jersey

Application April 16, 1941, Serial No. 388,783

47 Claims. (Cl. 12—47)

This invention relates to shoe machines and particularly to machines for breasting attached heels.

This operation is now accomplished by means of a knife which cuts from the tread surface of the heel to the attaching face at the breast line on the shank of the shoe, and for the full width of the heel, to form the breast surface by a single stroke. Due to the width of the cut and the amount of substance through which the knife must pass in making its cut, the heel, as well as the materials forming the bottom of the shoe, are subjected to extremely high pressures which frequently cause distortion of the heel and/or shoe bottom and which have a more or less damaging effect on the shoe in general. When, as is usually the case, the heel is made up of a plurality of lifts of leather, or similar compressible material, the lifts are individually compressed by the knife, as it passes through the heel, and, as the compressing force is relieved after the breasting cut has been completed, spring back to form a plurality of ribs, or ridges, on the breast surface which must be removed by abrading, or otherwise, to obtain the smooth breast surface required by the trade.

The compression of the materials forming the bottom of the shoe by the knife introduces another serious problem in heel breasting since, as the compressing force is immediately relieved when the knife has passed through the heel at the bottom of its stroke, these materials tend to spring back and press the shank surface against the sharp edge of the knife, or, the resistance on the knife being relieved, the knife may overtravel and cut into the shank surface. The resulting marking of, or even slight cutting into, the shank surface of the shoes, is very detrimental to their quality and value.

In machines of this type, the breast surface, which is usually substantially straight lengthwise and concave lengthwise of the shoe, is shaped by the knife itself, thus requiring a different knife for each change in lengthwise curvature of the heel breast, and the cutting edge of the knife must be shaped by grinding so as to conform, at least substantially, to the contour of the shank at the breast line of the particular type of shoes being handled. Accordingly, where a great variety of heel breasts on shoes of different types are to be cut, numerous breasting knives must be available and considerable time spent in grinding and fitting their cutting edges to different shanks.

It is the principal object of this invention to provide an improved heel-breasting machine which is capable of cutting substantially smooth breast surfaces of various lengthwise curvatures on the heels of shoes of all types in an efficient and satisfactory manner and without distortion

of, or damage to, the shoe parts or the use of a plurality of different and separately fitted breasting knives. To this end, there is provided, as an important feature of this invention, a novel heel-breasting tool which cuts heightwise of an attached heel and progressively, with a series of light cuts, across the heel from one side of the heel to the other, together with means for supporting and moving a shoe continuously to feed its heel past the tool for breasting the heel. More specifically, the tool is chisel-like in form and is rapidly reciprocated to remove only a light chip at each stroke, as the heel is moved slowly past the tool, thus avoiding any possibility of distortion of the heel or of the materials forming the bottom of the shoe and insuring a smooth breast surface.

In accordance with further features of the invention, means are provided for shifting the tool lengthwise of the heel during the breasting action to cause the tool to cut a breast surface that is curved in a lengthwise direction and also for shifting the stroke of the tool so that it terminates, in one direction, always at the line of demarcation between the attaching face of the heel and the lower surface of the shank at the breast line. More particularly, the lengthwise shifting of the tool is accomplished by means which are readily replaceable for producing different breast surface curvatures with the same tool, while the shifting of the stroke of the tool is effected by a shank-engaging element so that all types of shank contours are readily accommodated. Also, to avoid possible binding of the tool on the continuously moving heel, a still further feature of the invention resides in the provision of means for moving the tool laterally of its stroke and widthwise of the heel to follow the heel during the breasting operation.

With the view of expediting the breasting of heels with the above-mentioned novel breasting tool, further features of the invention include the provision, in my improved machine, of a plurality of novel shoe-supporting devices each arranged, preferably on a revolvable turret, for movement quickly from a loading position, conveniently located at a point remote from the tool, to a working position adjacent to the tool, then slowly to feed the heel of a shoe supported thereon past the tool, and finally quickly to return to the loading position. The arrangement is such that the operator can load and unload on one shoe-supporting device while the tool is operating on the heel of a shoe in another supporting device with the result that the tool is not long idle and the handling of shoes proceeds continuously at the will of the operator. Preferably, the novel supporting devices are arranged to rotate on the turret so that the shoe can be loaded heel-end away from the operator and pre-

sented to the tool in the same orientation. More specifically, the novel shoe-supporting devices comprise improved jack constructions having forepart supporting means, yieldable to permit leveling of the shoes, a last-supporting member, and a cooperating heel-clamping member, the latter being manually operable initially to clamp the heel end of the shoe, and simultaneously to lock the forepart-supporting means. Means are also provided on the improved machine, in accordance with this feature of the invention, for applying additional pressure to the clamping member, just prior to the heel-breasting operation, for stabilizing the jacks during the breasting operation, and for automatically releasing the shoe after completion of the breasting operation, the whole arrangement being such that shoes are easily loaded into and removed from the machine and are firmly supported during the action of the tool on their heels.

The above and other objects and features of the invention will be apparent in the following detailed description of the preferred embodiment thereof, illustrated in the accompanying drawings, and will be pointed out in the appended claims.

In the drawings,

Fig. 1 is a view in side elevation of a machine embodying this invention;

Fig. 2 is a view, also in side elevation but at an enlarged scale, of a portion of the head of the machine shown in Fig. 1 with part of the casing in section to disclose the mechanism therein contained;

Fig. 3 is a front view of the head of the machine with the casing cover broken away to expose the enclosed mechanism and showing the upper parts of one of the shoe-supporting jacks of the machine;

Fig. 4 is a perspective view of a heel-clamping assembly forming a part of each shoe-supporting jack;

Fig. 5 is a timing chart showing the movements of the shoe-supporting jacks and the turret speeds during the operation of the machine;

Fig. 6 is a diagrammatic view showing the path of movement of the tool during a single reciprocation thereof; and

Fig. 7 is a plan view of a portion of the machine showing cam devices associated with the heel-clamping assemblies.

Referring to Fig. 1, the illustrated machine has a base 10 on which is mounted an upwardly extending standard 12 carrying at its top an overhanging head 14. A circular turret 16 is rotatably mounted in front of the standard, and beneath the head, on a post 17 rising from the base. Supported at diametrically opposite points on the turret are two shoe-supporting devices, each comprising an upright 18 having an enlarged supporting flange 20 at its lower end, and a downwardly projecting shaft portion 22, journaled in a bearing boss 24, forming part of the turret. Associated with each of these uprights is a jack post 24 having an upper adjustable portion 25 carrying a last pin 26, a heel-clamping assembly 28, forepart-supporting pads 30, and a clamping handle 32. These supporting devices will be described in detail below, and, in Fig. 1, one is shown supporting a shoe for breasting of its heel, while the other is empty and in its loading position. A bevel-ring-gear 34 is secured to the lower side of the turret and meshes with a pinion 36 on a power shaft 37. At their lower ends the shafts 22 are provided with cam arms 38, 38,

each of which has a cam roll 39 cooperating with a face cam 40 secured to the base 10.

During the operation of the machine, the turret is revolved about the post 17 at different speeds, in the manner illustrated in Fig. 5, i. e., at a slow speed while each jack is in loading or breasting position, and at a higher speed while the jacks are traveling between these positions. As the turret revolves, the shoe-supporting jacks are rotated on the turret, first a half-turn in one direction and then back to their original positions; these rotational movements being effected by the cam 40 acting through the arms 38, 38, and occurring during a major part of the two high-speed turret revolution intervals, as shown in Fig. 5. The supporting jacks, and hence the shoes carried thereby, are held against rotation likewise by means of the cam 40 and the cam arms 38, 38, during each slow-speed turret revolution interval, and for a part of each high-speed turret revolution interval, while the breasting cut is being made and the loading operation performed, see Fig. 5. In the illustrated machine the shoe-supporting devices are so held in rest positions during turret movements of about sixty degrees, and the breasting and loading operations are performed during movements of the turret of about forty degrees. These values have been arbitrarily selected, for purposes of illustration, and may be varied to suit different conditions by changing the shape of cam 40. This makes it possible to load the shoes conveniently, heel-end away from the operator, on one side of the revolving turret, and to present them to the breasting knife, at the other side, in the same orientation.

The breasting operation is performed by means of a reciprocating chisel-like knife 42, Figs. 1, 2 and 3, operated by mechanism to be described in detail below, which cuts heightwise, from the tread surface to the attaching face at the breast line, progressively across the heel H of a shoe S, on one of the jacks, as the turret revolves slowly, and while the jack is held in fixed relation to the turret. At the completion of the slow-speed interval, the turret revolves quickly through the succeeding high-speed interval to present the heel of a shoe on the other jack to the knife and to return the first jack to loading position. In order that the edge of the attaching face may conform exactly to the lateral curvature of the shank portion Sh of the shoe, at the breast line, the depth of the knife stroke is varied, during the progress of the heel by the knife, by a roller 44, operating through associated mechanism, which traverses the shank just in front of the knife, Figs. 1, 2 and 3. The arrangement is such that the lowermost point of each knife stroke coincides with the juncture of the heel and shank at that particular point on the breast line widthwise of the shoe.

As the breasting operation proceeds, the position of the knife lengthwise of the shoe is changed by a control means comprising a roll 51 (Fig. 2) engaging a cam path provided in a heel-clamping plate 50, forming part of the heel-clamping assembly 28. The shape of the cam path determines the curvature of the heel breast, and plates having differently shaped cam paths are provided for a wide selection of breast surface curvatures. Since the heel moves continuously during the breasting operation, the knife is shifted laterally during its cutting and return strokes at a rate corresponding to the feeding movement and is quickly returned to its original position just prior

to the next succeeding cutting stroke, by mechanism to be described. The knife is reciprocated at a very high rate of speed so that adjacent cuts are very closely spaced and a substantially smooth breast surface produced. Because of the lightness of the chip removed by the knife there is little or no distortion of the heel substance or of the shoe bottom by the action of the knife, and the shank-engaging roller 44 with its associated mechanism insures a full cutting-through of the heel to the shank along the entire breast line without any possibility of overtravel of the knife which might mar or damage the shank.

The high and low speed turret rotations are obtained by selectively rotating the shaft 37 at two speeds. A motor 60, supported in the base 10, drives a main shaft 66, provided also with a hand wheel 68, through a belt 62 and a pulley 64. Shafts 80 and 82, journaled in the standard 12, are in turn driven from the shaft 66 by belts 70, 72 and pulleys 74, 73, 74 and 76. A cone clutch 86 is associated with the shaft 80 for connecting this shaft to a gear 94 which forms a part of a reducing gear train comprising this gear and gears 100, 102 and 96, and a similar type of cone clutch 88 is associated with shaft 82 for connecting this shaft directly to the power shaft 37. The gear 96 is connected to the power shaft 37 by means of an overrunning clutch 98. Pivoted to the standard 12 is a clutch-operating lever 90 associated with each of the clutches 86 and 88 in the manner shown. A spring 92 is arranged to urge the clutch 86 toward engaged position and to disengage clutch 88, through lever 90, and a control rod 104 is slidably mounted in the standard for engagement with the lever 90.

In Fig. 1 the parts are shown in position for obtaining a slow-speed drive of shaft 37 through the belt 72, shaft 80, clutch 86, reducing gear train 94, 100, 102 and 96 and the overrunning clutch 98. When the rod 104 is shifted slightly to the right the clutch 86 will be disengaged before the clutch 88 is engaged, and a neutral position is obtained in which no power is transmitted to the shaft 37. On movement of the rod 104 further to the right the clutch 88 will be engaged and the high-speed turret drive obtained through the belt 70, shaft 82, clutch 88 and shaft 37, the overrunning clutch 98 now permitting the shaft 37 to turn without rotating the gear 96 of the reducing train.

In the illustrated machine the power drive is held in slow-speed position positively during the two slow-speed intervals of the turret at the end of which the rod 104 is automatically moved to neutral position. The high-speed drive for revolving the turret to move the shoe-supporting devices between loading and working position is then obtained by the operator. This is accomplished by means of a foot treadle 124, operating through a linkage arrangement including a rod 122, bell-crank lever 120, rod 118 and lever 116, to move a lever arm 106 to the right and shift the rod 104 to engage clutch 88. Connected to the arm 106, which is integrally formed with the lever 116, is a roll 108 which rides on a cam track 110 formed on the upper surface of the gear 34. This cam track has two oppositely positioned throws 112, and when the roll is in either of these throws the rod 104 assumes its extreme left-hand position (Fig. 1) and slow-speed drive is obtained. Keeper plates 114, 114, flared at their leading edges 115, prevent displacement of the roll away from the cam throws 112 by in-

advertent treadle movement during this period. When the turret is turned sufficiently to bring the roll up on either of the long dwells of the cam 110 the rod 104 is shifted to the neutral position and the turret stops unless the treadle is depressed for the high-speed drive. At the end of each high-speed drive interval the flared leading edge 115 of the next keeper plate will engage the roll 108 and move it down into the throw 112 whereupon slow-speed turret drive is again resumed. A spring 119, which is interposed between the rod 118 and the bell-crank lever 120, permits this movement to be effected, although the operator may still hold the treadle 124 down. Accordingly, so long as the treadle is depressed, the machine will continuously operate through its recurrent cycles of high and low-speed turret rotation, see Fig. 5, but will automatically stop at the end of each slow speed interval, if the treadle is then released.

The shoe-supporting devices, or jacks, carried by the turret, are identical in construction and one of these will now be described in detail with particular reference to Figs. 1, 3 and 4. Each jack post is supported on a rockshaft 130, journaled in the lower part of its upright 18, and has an outwardly projecting foot 132 which limits outward swinging movement of the jack post by engagement with a raised boss 131 formed on the flange 20, see Fig. 1. Keyed to a projecting end of the rockshaft is an arm 134 which is connected to a second arm 138, pivoted to the upright, at a point considerably above the flange 20, by means of a rod 136. The arm 138 forms one link of a toggle having a second link 140 connected at its outer end to a downwardly extending bar 142. The elements 134, 136, 138, 140 and 142 are duplicated on the opposite side of the upright 18, which is of hollow open-sided construction and provided at its upper end with forwardly projecting ears 146, 146 terminating in bosses 147, 147, see Figs. 1 and 4.

The last pin 26 is carried by the upper portion 25 of the jack post, which is adjustable vertically by means of a threaded adjusting sleeve 144 and is held in adjusted position by means of a clamp nut 145. To avoid confusion, the last pin and upper portion of element 25 has been omitted from Fig. 4, its position between the ears 146, 146 being readily apparent in Figs. 1 and 3. The bars 142, 142 are journaled on studs 148, 148, secured in the bosses 147, 147, and above these studs the bars are each enlarged to form supporting brackets 150, 150, extending upwardly and inwardly over the ears 146, Fig. 4.

The forepart-supporting pads 30, 30 are carried on hollow rods 152, 152 clamped in split bearing portions of the brackets 150, 150 by screws 151. A cross piece 160, Figs. 1 and 3, is adjustably mounted on the rods 152, 152 by means of split bearing portions 162, 162, provided with clamping screws 164, 164, and is formed with vertical guide bearings 166, 166. Slidable in these guide bearings are vertically extending rods 170, 170. These rods, which are supported vertically against stop collars 171, 171, Fig. 1, by relatively light springs 172, 172, carry at their upper ends the forepart-supporting pads 30, 30 that are formed as the outer ends of inwardly extending arms 173, 173 adjustably mounted in bifurcated end portions of these rods. When the jack post is swung forward the toggles 138, 140 are broken and the parts assume the positions shown at the left-hand side of Fig. 1, with the rods 152, 152 tipped down and the

forepart-supporting pads 30, 30 held yieldingly in their uppermost positions by the springs 172, 172. As a shoe is placed on the last pin 26, which extends from a block 174, mounted for universal movement on a ball 175, Fig. 3, its forepart will rest on the pads 30, 30. By raising the outer ends of the rods 152, 152 the jack post and last pin will be moved inwardly to the position shown at the right, Fig. 1, thus bringing the heel H of the shoe beneath the heel-clamping plate 50. Before operating the heel-clamping plate, to clamp the shoe on the jack post, the shoe may be leveled to bring the tread surface of forepart and heel into the same horizontal plane, by depressing its forepart, the springs 172, 172 permitting this leveling action.

Extending through apertures 176, 176 which open into the guide bearings 166, 166, are friction binding rods 154, 154. These rods are provided with flattened faces 180, 180 which slidably engage the rods 170, 170 and at their inner ends are journaled in the brackets 150, 150. In moving the heel-clamping plate against the heel, after the shoe has been suitably leveled, the rods 154, 154 are turned, by mechanism about to be described, so that their flattened faces bind against the rods 170, 170, thus locking the latter rods firmly in position to support the forepart of the shoe. The turning of the rods 154, 154 is effected through arms 182, 182, Fig. 4, adjustably mounted on the inner end of these rods by means of clamping screws 184, 184.

Slidably mounted in spaced lower and upper guide bearings 186, 186 and 190, 190, formed in the upper end of the upright 18, are vertically extending rods 188, 188. A crossbar 192 is clamped to these rods at each of its ends by clamping portions 194, Fig. 4, and is provided with a rib 196 having rack teeth 198. Adjacent to the upper guide bearings the upright 18 has rearwardly extending ears 200, 200 in which is journaled a cross shaft 202. The cross shaft is held against axial movement by the hub portions of two cranks 204, 206 secured to its opposite ends; the hub of the last-mentioned crank bearing against a hub portion 201 of the clamping handle 32 which is secured to a sleeve 203, rotatably mounted on the shaft. Pinned to the mid-portion of the cross shaft is a pinion 210 meshing with the rack teeth 198, and fixed to the sleeve 203. On the opposite side of the ear 200 from the hub 201 is a hub portion 205 provided with an upwardly extending arm 212 and a rearwardly extending arm 218. A pawl 214, having an operating arm 207, is pivoted to the upper end of the arm 212 and is held yieldingly in engagement with teeth on a ratchet wheel 211, formed integrally with the pinion, by a spring 216. Journaled on the outer end of the rearwardly extending arm 218 is a cam roller 220. A spring-actuated detent 222, supported on the upright 18, is arranged to engage the teeth of the ratchet wheel 211 and normally to hold the pinion 210 against rotation in a clockwise direction, as viewed in Fig. 4.

The cranks 204, 206 are each connected by straps 224, 224 to rocker arms 226, 226, pivoted on the ears 146, 146 adjacent to the brackets 150, 150 and provided with cam surfaces 228, 229. These cam surfaces cooperate with surfaces 239, 239 on the arms 182, 182, secured to the binding rods 154, 154, so that these rods are turned to binding position against the rods 170, 170, when the cranks 202, 204 are turned in a counterclockwise direction, and are shaped, with

a rise and a dwell, so that they first swing the arms 182, 182 upwardly and, on further turning movement of the cranks, hold the arms in binding position.

5 The heel-clamping assembly, designated generally by the reference character 28, Fig. 4, includes a cross plate 236 slidably mounted on the rods 186, 186 and yieldingly supported by means of light coil springs 234, 234 surrounding these 10 rods and resting on the upper ends of the guide bearings 190, 190 of the upright 18. Above the cross plate are relatively heavy coil springs 238, 238 bearing against adjustable stop collars 248, 240, on the uppermost ends of these rods. Secured to the cross plate is the heel-clamping plate 50 which comprises a rearwardly extending base 242 having a tongue 246 fitting into a corresponding groove in the plate 236, see Fig. 2, and provided with an adjusting slot 244 for receiving a locking screw 250. At its forward end the heel-clamping plate is thickened and formed with an arcuate cam groove 253 having flared ends 260, 260. The adjustable portion 25 of each jack post is 25 set for the particular height of heel being worked upon so that the lower surface of the thickened forward end of the heel-clamping plate just clears the toplift of the heel of a shoe placed in the heel-supporting device when the jack post 30 is swung into the position shown in Fig. 1. After a shoe has been placed in the supporting device and the jack post moved into this position, the operator levels the forepart of the shoe, the springs 172, 172 permitting appropriate movement of the shoe-supporting pads 30, 30. Now, while holding the shoe leveled, he pulls the handle 32 toward him, until it strikes a stop pin 213 on the upright 18, see dotted line 35 position of the handle in Fig. 1. Since the handle is connected to the pawl-carrying arm 212, through the sleeve 203, this effects a partial rotation of the ratchet wheel 211 and the pinion 210, and also of the shaft 202, in a counterclockwise direction, Fig. 4, against the action of a 40 coil spring 232, secured at one end to one of the ears 200 and at the other to a hub 233 on the gear 210. This rotation of the gear 210, operating through the rack 198, depresses the rods 188, 188 and forces the heel-clamping plate against the top lift of the heel, through the action of the strong springs 238, 238, to clamp the last shoe initially between the clamping plate and last-pin block 174. The rotation of the shaft 202 turns the cranks 204, 206 and causes cam surfaces 228, 228 to turn the binding rods 154, 154 to binding position against the rods 170, 170, thus locking the forepart-supporting pads 30, 30 in the positions they assumed during the leveling of the shoe. A spring 215 returns the handle 32, arm 212 and pawl 214 to their original positions, 50 determined by a stop pin 217 on upright 18 (Fig. 4), while the spring-actuated detent 222 engages the teeth of the pinion 210 to hold the parts in shoe-clamping and shoe-supporting position.

55 The loading of a shoe takes place during a slow-speed loading period of turret movement and while the jack is held against rotation with respect to the turret, see Fig. 5. The next period of 60 turret movement, which occurs at a high speed, brings the shoe beneath the head 14, a half-turn of the jack with respect to the turret having been effected to maintain the proper orientation of the shoe, whereupon slow-speed turret revolution is again resumed and the breasting operation performed as the heel is fed slowly past the

breasting knife 42 during this "breasting" period of turret revolution.

While the heel is being breasted the jack is stabilized (Fig. 1), by means of an extended rib 272 on the upright 18 which is arranged to fit nicely in a groove 270 formed by a shouldered block 271 secured to the front face of the standard 12 and the bottom face of a horizontal cam plate 274 secured to the block beneath a vertical cam plate 275. The cam plate 274 is formed with a lug 280, Figs. 1 and 7, arranged to trip the detent 222, after the "breasting" period of turret movement has been fully completed, thus releasing the ratchet wheel 211 and the pinion 210 to allow the springs 232, 234 to return the shoe-clamping and shoe-supporting parts to their original positions thereby releasing the shoe for removal from the jack.

The cam plate 275 comprises a rise 276, a dwell 278, and a vertical drop 279 on the opposite side from the dwell, see Figs. 1, 3 and 7. This rise is arranged to engage the roll 220, which is carried on the outer end of the arm 218, see Fig. 4, as the turret rotates to present the heel to the knife, and to effect a second turning of the pinion 210, and a consequent increase in the clamping pressure applied to the heel, during the period of action of the knife 42 on the heel, see Fig. 5. As the roll 220 passes off the dwell 278 the handle 32 and pawl-carrying arm 212 are returned to their original positions by the spring 215, while the detent 222 holds the parts in clamping position during the remainder of the breasting operation.

After the breasting operation has been completed the detent 222 is tripped by the lug 280 on cam plate 274, see Fig. 7, and, while the detent is held in tripped position, an overhanging cam finger 282, Figs. 3 and 7, engages the operating arm 207 of the pawl 214 and moves the pawl out of engagement with the ratchet wheel 211. Spring 232 now returns the shaft to its original position, such movement being limited by the engagement of the rocker arms 226, 226 with stop pins 284, 284, and at the same time springs 234, 234 elevate the plate 50 away from the heel.

As the shoe is thus released, after the turret moves through this "breasting" period, the operator, having in the meantime loaded a shoe into the other jack, depresses the treadle for high-speed turret revolution, at the end of which he removes the shoe which had just been released. Accordingly, loading of the shoe takes place while the heel breasting of a previously loaded shoe is effected, and, as the turret turns rapidly to present a loaded shoe to the breasting knife, there is no delay in the operation and the work proceeds continuously but with ample time afforded for loading, leveling of a loaded shoe, and shoe removal after breasting. The arcuate extent of each of the cam throws 112, 112 is such that the slow-speed "breasting" period begins somewhat before the widest heel would reach the breasting knife and continues after such a heel has passed beyond the knife, the periods of jack rest being considerably longer than the slow-speed "breasting" or "loading" periods, as shown in Fig. 5.

The knife-operating and controlling mechanism is contained within the head casing 14 which is provided with spaced main bearings 302, 304, Figs. 1 and 2, for the drive shaft 66. The head casing is enlarged to form a chamber 308, closed by a cover 310, which receives a crank

disk 306, carried by the drive shaft. The breasting knife 42, which is relatively narrow and chisel-like in form, is removably secured in the lower end of a knife slide 312 by a set screw 311. This slide, which is flush with the working side of the knife, see Fig. 2, passes up into the chamber 308 through an enlarged opening 314 in a boss 309 and is slidably mounted in a frame 316. A splash cover 315 rests on the boss 309, being held thereon by spring 313, and the slide 312 passes through this cover, as shown. The frame 316 is pivoted on a stud 318 secured to an upwardly extended portion 320 of a bracket member 322 which is supported for forward and backward sliding movement on studs 324 and 326, secured in the head casing by set screws 325 and 327. The knife slide is thus mounted for three kinds of movement, i. e., vertical reciprocating movement in the frame 316, sidewise swinging movement with the frame on the stud 318, and forward and backward sliding movement with the frame on the studs 324 and 326.

The vertical reciprocating movement, which produces the cutting action of the knife, is effected by a crank and linkage mechanism driven from the crank disk 306 on the main shaft 66, see Figs. 2 and 3. A connecting rod 330 journaled on a crank pin 329, secured to the crank disk, is connected by a pivot pin 331 to a link 332. The link 332 is pivoted on a stud 334 carried by a supporting bracket 336 secured to a rod 338. The stud 334 is extended rearwardly beyond the link 332 where it is of reduced size to receive a block 337, Fig. 2, slidably mounted in a guide groove 339 formed in the casing head 14. In this manner, turning of the bracket and rod 338 by forces applied thereto during the operation of the machine is prevented. The rod 338 is mounted in guide bearings 340 and 342 provided on the casing head 14, and on its lower end, which extends below and outside of the casing, is adjustably mounted an angular arm 348 carrying the shank-engaging roller 44. The arm 348 is enlarged to form a sleeve 350, which is slidably mounted on the rod 338, and journaled in this sleeve in a pin 382. The pin 382 extends through an elongated slot 386 in the rod and, at its central portion, has an eccentric 384, Fig. 3. An operating handle 388 is secured to the outer ends of the pin, and the arrangement is such that movement of the handle effects an adjustment of the roll 44 with respect to the rod 338. A spring-pressed pawl 390, engaging locking teeth 392, formed on an extending web of the sleeve, is provided for locking the parts in adjusted position. The locking effect of the teeth is sufficient to hold the roll fixed, due to its mechanical advantage over the small throw of the eccentric 384, while, at the same time, offering but slight resistance to manual movement of handle 388.

This rod also passes through an intermediate guide bearing and spring abutment 344, formed on an upwardly extending support 346 bolted to the bottom wall of the casing. A relatively strong compression spring 352, arranged between the lower face 356 of the guide bearing and spring abutment 344 and a collar 354 on the rod, urges the rod downwardly. When a shoe is in the machine and passing by the breasting knife 42, the roller 44 engages the shank of the shoe and elevates the rod against the action of the spring 352, thus determining the vertical position of the rod 338. A stop collar 339, adjustably secured to the upper end of the rod 338,

Fig. 2, is provided for limiting the downward movement of the rod when the roller passes off the shank portion of the shoe.

A second link 360 is secured at one end to the pivot pin 331 and journaled at its other end on a stud 362 mounted in the end of a swinging arm 364 having an enlarged hub portion 365 journaled on a stud 367, Figs. 2 and 3. The stud 362 has a spherical head 368 on which is mounted for universal movement a strap 370. This strap is universally connected by means of a spherically headed stud 372 to a projecting bracket 374 clamped to the knife slide 312 by a clamping screw 376. The links 332 and 360 form a toggle linkage which is lengthened and shortened by the connecting rod 330 as the crank disk is rotated. The upper end of this linkage, at stud 334, is fixed by the position of roller 44 and the action of the spring 352, while its lower end, at the stud 362, moves up and down as the linkage is shortened and lengthened, thereby swinging the arm 364 and imparting a reciprocating movement to the knife slide 312 which is connected thereto by strap 370. The linkage and crank throw are arranged so that the knife is elevated somewhat above the lower surface of the heel-clamping plate 50 and the tread surface of the top lift of the heel H at the uppermost end of its stroke, see Fig. 3, and so that it travels just slightly below the shank-engaging roller 44 on its down stroke.

As the heel moves past the reciprocating knife, the roller 44 rides over the curved shank portion Sh of the shoe S, Figs. 2 and 3, in front of the knife, and constantly changes the vertical position of the stud 334. Accordingly, the locus of the lowermost knife positions forms a curve which is complementary to, and coincident with, that of the shank. By suitably adjusting the relative vertical position of this curve, with respect to the path of the roll 44, this being accomplished by manipulation of the handle 388, the knife can be made to cut completely through the heel to the shank, but without entering the shank, at each stroke thereof, regardless of slight differences in the elevation of the shank at the breast line and at the zone traversed by the roller. By changing the position of the stop collar 339 the lowermost position of the roller can be changed to accommodate a considerable range of heel heights, it being understood, of course, that the plane of the bottom surface of the shoe is determined by the heel-clamping plate while the roller 44, together with the knife-actuating linkage, is shifted up or down, as the height of the heel and vertical position of the shank varies with different shoes. Where the height of the heel falls beyond this range, crank discs having different throws, together with connecting rods of appropriate length, may be substituted for those shown to shorten or lengthen the knife stroke, and the brackets 336 and 374 adjusted to suitably position the stroke and roll 44 vertically with respect to the plate 50. Thus, this machine can be readily adapted to breast heels of any height, from the extremely high heel for ladies' shoes shown to a low heel for a man's shoe.

Because of the relatively large diameter of the roller 44, as compared to the width of the knife 42, the linkage mechanism formed by links 330 and 360 will be appropriately elevated by engagement of the roller with the shank portion of the shoe before the reciprocating knife could contact the upper of an approaching shoe. Simi-

larly, at the opposite side of the shoe, the roller 44 will remain in engagement with the shank portion to hold the linkage mechanism elevated until the shoe has traveled well beyond the knife, thus avoiding contact of the knife with the upper. The stop collar 339 is adjusted so that the roller drops but slightly below the edge of the shank, thus insuring proper camming action of the roller by the shank as the shoe moves to pass the heel by the breasting knife. The cutting force of the knife, which is slight due to the small chip removed on each stroke, is sustained by the spring 352, and, in this manner, a somewhat yielding cutting action is obtained which is conducive to superior results in the character of the breast surface produced and also is easier on the heel and the supporting bottom material of the shoe. The spring 352 is strong enough to hold the roller 44 against the shank of the shoe at all times during the breasting action of the knife, but without undue pressure thereon, and also to force the knife through the heel on each of its strokes.

The heel moves continuously during the operation of the breasting knife 42 thereon, and means are provided for causing the knife to follow the heel during its cutting and return strokes. Referring to Fig. 6, the direction of movement of the heel H is indicated by the arrow at the upper part of this figure, and the broken line C extending vertically through the center of the heel represents a cut made by the knife during a single reciprocation at its completion and before the knife has returned. In the period of time it takes the knife to travel from the tread surface of the top lift down to the shank Sh and return, the heel moves to the left a short distance corresponding to the feeding increment per stroke. This is represented in Fig. 6, at an exaggerated scale, by the distance between points $x-z$. In actual practice, to obtain a relatively smooth breast surface, the speed of the knife, and the slow "breasting" speed of the turret, are so related that a feeding increment per stroke of between $\frac{1}{2}$ and $\frac{1}{8}$ of an inch is produced when the knife is reciprocated at a very rapid rate sufficient to reduce the time required for breasting a heel to a fraction of a minute. With feeding increments of this magnitude the chisel-like knife, which has a somewhat rounded cutting edge, will produce a substantially smooth breast surface on a heel and one that requires little, if any, subsequent smoothing-up or scouring.

In order that the knife cut may extend vertically of the heel, and also to avoid binding of the knife during its return stroke, the path of the knife must be triangular, following the dotted lines from point x to point y , to point z , and then returning to its original position before starting its next succeeding stroke. This kind of knife movement is obtained by swinging the frame 316, in which the knife slide 312 is carried, about its pivot point equal distances from the vertical and in timed relation to the knife stroke, by the following mechanism. A strap 394 is connected at one end to an ear 396, extending downwardly from the lower part of the frame 316, by means of a ball joint 398, and at its other end is similarly connected, by a ball joint 399, to an arm 400 which is secured to one end of a shaft 402 journaled in the casing head 14, Figs. 2 and 3. The other end of this shaft extends through the rear wall of the casing head, Fig. 2, where it is provided with a second arm

404 carrying at its outer end a cam roller 406. A face cam 408 is secured to the main shaft 66 by means of a pin 410 and has a cam path 412 in which the roller 406 rides. The cam path 412 is formed so as to have a gradual rise 413 throughout the most of its extent and terminating in an abrupt drop 415, see Fig. 3.

The timing of the cam with respect to the actuation of the knife is such, and the arms 400 and 402 are so arranged, that the knife is caused to follow a triangular path, as indicated by the dotted lines on Fig. 6; starting its cut somewhat to the right of the vertical, swinging to the left so that the cutting edge of the knife moves laterally at exactly the same rate as the heel during its stroke to produce a vertical cut, represented at its completion by the broken line C in Fig. 6; then continuing this swinging movement at the same rate during the return stroke of the knife on the opposite side from the vertical so that the knife follows its cut, which moves to the left to point z; and finally quickly swinging the knife to the right to return it to its original position, after it has passed beyond the top lift and before it starts its next succeeding stroke. It will be understood that in practice the actual displacement of the knife laterally on each side of its vertical position will be slight, e. g., $\frac{1}{64}$ of an inch, when the feeding increment is $\frac{3}{16}$ of an inch, and that the angle of swing of the frame 316 will be very small.

During the action of the knife 42, the heel is moved in an arcuate path of relatively large radius of curvature by virtue of the revolution of the turret and the fact that the jack, on which the shoe is mounted, is fixed with respect to the turret at this time. In order to produce concave breast surfaces of smaller radii of curvature, such as would be ordinarily required, the knife is shifted lengthwise of the heel as the heel is moved by the knife during the breasting operation. This shifting movement is effected by sliding the bracket member 322, which supports the knife-slide carrying frame 316, backward and forward on its supporting studs 324 and 326 by the following mechanism. The cam roll 51 is mounted on the end of a pin 420 adjustably secured by a clamp screw 422 in the outer end of a lever 424, Figs. 2 and 3. The arm 424 is secured with capacity of angular adjustment, by means of a clamp screw 423, to a shaft 426 journaled in a bearing portion 428 formed on the casing head 14. This shaft extends upward into the lower part of the chamber 303 where it is provided with an integrally formed arm 430. At its outer end the arm 430 is formed with a forked portion 432 which embraces a cylindrical extension 433 on the lower part of the bracket 322, see Fig. 2. Swinging movement of the lever 424 is thus effective to produce forward and backward shifting movement of the bracket member 322 and the knife-slide carrying frame 316.

As the jack approaches the breasting knife, during movement of the turret at a slow-speed interval, the roller 51 is guided into the cam grooves 258 by the flared ends 260, 260, the side walls of hole 314 holding the roll roughly centered with respect to the flared ends, and thereafter, during the action of the knife to breast the heel, the position of the knife lengthwise of the heel will be governed by the position of the roller 51 which, in turn, is determined by the shape of the cam groove 258. Accordingly, by appropriately shaping this cam groove, breast

surfaces of any desired curvature may be produced. As previously explained, the groove 258 is formed in an enlarged portion of the heel-clamping plate 50 which is readily replaceable by other clamping plates having cam grooves of different curvature. By loosening the clamp screw 250 the plate 50 is freed for adjustment to vary the position of the breast surface lengthwise of the heel.

10 The operation of the several mechanisms which comprise the illustrated machine having been explained above, as these mechanisms were described, it will be necessary now only to outline briefly the operation of the machine as a whole. This will be done by following the action of the machine which occurs during a single complete rotation of the turret 16. Referring to the left-hand jack, Fig. 1, and assuming the turret to be just beginning its slow-speed "loading" interval of revolution, with the motor 60 running to drive the turret and main shaft 66; the operator places a shoe in the jack, with its last thimble on the last pin 26 and with its forepart resting on the pads 30, 30, the adjustable portion 25 of the jack post having been previously set to accommodate the particular height of heel to be breasted. The rods 152, 152 are now lifted to swing the jack post rearwardly, thus bringing the heel of the shoe underneath the heel-clamping plate 50. After leveling the shoe, the operator grasps the handle 32 and pulls it toward him, initially clamping the heel beneath the heel-clamping plate and cone of the last on the last-pin block 174, see Fig. 2, and also locking the rods 170, 170 to hold the pads 30, 30 firmly in forepart-supporting position. The handle is now released, the pawl 222 holding the parts in shoe-clamping position, as explained above. These operations are quickly performed and while the turret completes its slow-speed "loading" interval of revolution with the jack held fixed thereon.

As the cam roller 103 moves up onto the dwell of cam 110, the operator depresses the treadle 124 to initiate the high-speed interval of turret revolution, thus quickly transferring the jack to the right-hand position in Fig. 1, or he may have previously depressed the treadle, in which case the spring 119 moves the lever arm 116 to engage the high-speed clutch 88. When the turret reaches the slow-speed "breasting" interval a keeper plate 114 will depress the roll 103 to disengage the clutch 88 and engage the low-speed clutch 86, whereupon the slow-speed turret speed is resumed. The heel H now approaches the rapidly reciprocating breasting knife 42, but before reaching it the following actions take place: the roller 51 enters the cam groove 258, thus taking control of the forward and backward position of the knife 42, and the roller 44 engages and rides up onto the shank Sh, to elevate the knife-actuating linkage and thus position the knife stroke vertically so that the knife cuts completely through the heel substance on each stroke, stopping exactly at the shank. Before the heel reaches the knife, the additional clamping pressure is applied by the cam 276 in the manner explained above.

70 While the heel is being breasted the operator is free to load another shoe onto the empty jack, which will be in loading position and moving at a slow speed. After breasting of a heel is completed the revolution of the turret proceeds until the keeper plate 114 passes beyond the roller 103 allowing it to be elevated onto the dwell of cam 75 110. At this time, if the other shoe has been

loaded, as will usually be the case, the operator, unless he has been holding the treadle 124 down, depresses this treadle to initiate high-speed turret revolution quickly to transfer the shoe which has just been loaded to breasting position, and to return the jack carrying the shoe, the heel of which has just been breasted, to loading position where it may be readily removed, the shoe-clamping and shoe-supporting means having been automatically released by the action of lug 280 and finger 282, as explained above.

The operation thus proceeds continuously as the operator loads and unloads the jacks as they pass by him at the front of the machine. When it is desired to cut breast surfaces of different curvature another heel-clamping plate 59, having an appropriately curved cam path, will be substituted, and the depth of the breasting cut can be varied by loosening the clamping screw 250 and shifting the plate on the cross-plate 236. Also, as has already been pointed out, the stroke of the knife can be varied, and the vertical position of roller 44 changed, to accommodate heels of different heights.

Having described my invention, what I claim as new and desire to secure by Letters Patent of the United States is:

1. A heel-breasting machine comprising a reciprocating tool arranged to cut heightwise of an attached heel, and means for supporting and moving a shoe to feed its heel past the tool, while the tool is operating, progressively to breast the heel from side to side.

2. A heel-breasting machine comprising a reciprocating tool having a relatively narrow cutting edge arranged to cut heightwise of an attached heel from tread surface to attaching face at the breast line, and means for supporting and moving a shoe relatively to the tool for feeding its heel past the tool, while it is operating, to cause the tool to breast the heel progressively, with a series of light cuts, from one side to the other.

3. A heel-breasting machine comprising a reciprocating tool arranged to cut heightwise of an attached heel from tread surface to attaching face at the breast line, means for supporting a shoe, and means for effecting relative movement between said tool and said supporting means to feed the heel of the shoe past the tool, while it is operating, for causing the tool to breast the heel progressively, by means of a series of cuts, from one side to the other.

4. A heel-breasting machine comprising a reciprocating tool arranged to cut heightwise of an attached heel, means for supporting and moving a shoe to feed its heel past the tool, while it is operating, for causing the tool to breast the heel progressively from one side to the other, and means for shifting said tool lengthwise of the heel during said breasting operation.

5. A heel-breasting machine comprising a reciprocating tool arranged to cut heightwise of an attached heel and progressively across the heel from one side to the other, means for supporting a shoe for widthwise movement relative to the tool for feeding its heel past the tool to breast the heel, and means for shifting the tool lengthwise of the heel during said widthwise movement to cause the tool to cut a breast surface which is curved lengthwise of the heel.

6. A heel-breasting machine comprising a reciprocating tool arranged to cut heightwise of an attached heel and progressively across the heel from one side to the other, means for support-

ing a shoe for widthwise movement relative to the tool for feeding its heel past the tool to breast the heel, guide means for said tool, and means for moving said guide means to shift the tool lengthwise of the heel during said widthwise movement thereof to cause said tool to cut a breast surface which is curved lengthwise of the heel.

7. A heel-breasting machine comprising a reciprocating tool arranged to cut heightwise of an attached heel and progressively across the heel from one side to the other, means for supporting and moving a shoe relatively to the tool to feed its heel past the tool for breeding the heel, guide means for the tool, and means comprising a cam device movable with the shoe for moving said guide means to shift the tool lengthwise of the heel during said relative movement of the shoe for causing the tool to cut a breast surface which is curved lengthwise of the heel.

8. A heel-breasting machine comprising a reciprocating tool arranged to cut heightwise of an attached heel and progressively across the heel from one side to the other, means for supporting and moving a shoe relatively to the tool to feed its heel past the tool for breeding the heel, guide means for the tool slidably laterally of the path of movement of the shoe, and means comprising a cam device movable with the shoe for sliding said guide means to shift the tool lengthwise of the heel during relative movement of the shoe for causing the tool to cut a breast surface which is curved lengthwise of the heel, said cam device being arranged for ready replacement by other cam devices adapted to cause the tool to cut breast surfaces of different curvatures.

9. A heel-breasting machine comprising a reciprocating tool arranged to cut heightwise of an attached heel and progressively across the heel from one side to the other, means for supporting and moving a shoe to feed its heel past the tool for breeding the heel, and means for shifting the stroke of the tool, as the heel moves by the tool, so that the stroke terminates always on a line between the attaching face of the heel and the surface of the shank at the breast line.

10. A heel-breasting machine comprising a reciprocating tool arranged to cut heightwise of an attached heel from tread surface to attaching face at the breast line and progressively across the heel from one side to the other, means for supporting and moving a shoe in a widthwise direction to feed its heel past the tool for breeding the heel, and means engaging the shank of the shoe for shifting the stroke of the tool as the heel moves by the tool so that the stroke terminates, in one direction, always at the line of demarcation between the attaching face of the heel and the surface of the shank at the breast line.

11. A heel-breasting machine comprising a reciprocating tool arranged to cut heightwise of an attached heel from tread surface to attaching face at the breast line and progressively across the heel from one side to the other, means for supporting and moving a shoe widthwise in a plane normal to the direction of the stroke of the tool to feed the heel past the tool for breeding the heel, means for operating the tool including a linkage having a movable support, and means engaging the shank of the shoe for moving said linkage support to shift the stroke of the tool relatively to the plane of movement of the shoe, as the heel moves by the tool, so that the stroke terminates, in one direction, always at the line of demarcation between the attaching

face of the heel and the surface of the shank at the breast line.

face of the heel and the surface of the shank at the breast line.

12. A heel-breasting machine comprising a reciprocating tool arranged to cut heightwise of an attached heel from tread surface to attaching face at the breast line and progressively across the heel from one side to the other, means for supporting and moving a shoe widthwise in a plane normal to the direction of the stroke of the tool to feed its heel past the tool for breasting the heel, operating means for the tool including a linkage and a movable support therefor, and means associated with said support and adapted to engage and follow the shank portion of the shoe for shifting the stroke of the tool relatively to the plane of movement of the shoe, as the heel moves by the tool, so that the stroke terminates, in one direction, always at the line of demarcation between the attaching face of the heel and the surface of the shank at the breast line.

13. A heel-breasting machine comprising a reciprocating tool arranged to cut heightwise of an attached heel from tread surface to attaching face at the breast line and progressively across the heel from one side to the other, means for supporting and moving a shoe widthwise in a plane normal to the direction of the stroke of the tool to feed its heel past the tool for breasting the heel, operating means for the tool including a linkage and a movable support therefor, and a roller associated with said support and adapted to engage and follow the shank portion of the shoe for shifting the stroke of the tool relatively to the plane of movement of the shoe, as the heel moves by the tool, so that the stroke terminates, in one direction, always at the line of demarcation between the attaching face of the heel and the surface of the shank at the breast line.

14. A heel-breasting machine comprising a reciprocating tool arranged to cut heightwise of an attached heel from tread surface to attaching face at the breast line and progressively across the heel from one side to the other, means for supporting and moving a shoe widthwise in a plane normal to the direction of the stroke of the tool to feed its heel past the tool for breasting the heel, operating means for the tool including a linkage and a movable support therefor, a roller associated with said support and adapted to engage and follow the shank portion of the shoe for shifting the stroke of the tool relatively to the plane of movement of the shoe, as the heel moves past the tool, so that the stroke terminates, in one direction, always at the line of demarcation between the attaching face of the heel and the lower surface of the shank at the breast line, and means for adjusting said roller on said supporting member to vary the relative position of the tool stroke thereto to compensate for the slope of the shank from the point of engagement of said roller to the breast line.

15. A heel-breasting machine comprising a reciprocating tool arranged to cut heightwise of an attached heel and progressively across the heel from one side to the other, means for supporting and moving a shoe to feed its heel past the tool for breasting the heel, said means being arranged continuously to move the heel past the tool, and means for shifting the tool laterally of its stroke to cause the tool to follow the moving heel during its cutting action thereon.

16. A heel-breasting machine comprising a reciprocating tool arranged to cut heightwise of an attached heel from tread surface to attaching

face at the breast line and progressively across the heel from one side to the other, means for supporting a shoe for movement relative to the tool to feed its heel past the tool for breasting the heel, said means being arranged continuously to feed the heel past the tool during the action of the tool thereon, and means for moving said tool laterally of its stroke and widthwise of the heel while it is in cutting engagement with the heel at the same rate as said feeding movement thereby to cause the tool to follow the moving heel and avoid binding of the tool thereon.

17. A heel-breasting machine comprising a reciprocating tool arranged to cut heightwise of an attached heel from tread surface to attaching face at the breast line and progressively across the heel from one side to the other, means for supporting and moving a shoe to feed its heel continuously past the tool to breast the heel, guide means for said tool arranged for movement laterally of the stroke of the tool, means for operating the tool, and means associated with said operating means for moving the guide means to cause the tool to follow the continuously moving heel during its cutting action thereon.

18. A heel-breasting machine comprising a reciprocating tool arranged to cut heightwise of an attached heel from tread surface to attaching face at the breast line and progressively across the heel from one side to the other, means for supporting a shoe for continuous feeding movement of its heel past the tool to breast the heel, guide means for the tool comprising a pivotally mounted member arranged to swing the tool laterally of the direction of its stroke, means for operating the tool, and means associated with said operating means for swinging the guide means to cause the tool to follow the continuously moving heel during its cutting action thereon.

19. A heel-breasting machine comprising a reciprocating tool arranged to cut heightwise of an attached heel from tread surface to attaching face at the breast line and progressively across the heel from one side to the other, means for supporting a shoe for continuous feeding movement of its heel past the tool to breast the heel, guide means for the tool comprising a pivotally mounted member arranged to swing the tool laterally of the direction of its stroke, means for operating the tool, and means including a rotary cam associated with said operating means for swinging the guide means to cause the tool to follow the continuously moving heel during its cutting action thereon.

20. A heel-breasting machine comprising a reciprocating tool arranged to cut heightwise of an attached heel from tread surface to attaching face at the breast line and progressively across the heel from one side to the other, means for supporting a shoe for movement of its heel past the tool to breast the heel, means for shifting said tool lengthwise of the heel during the breasting operation to cause the tool to cut a breast surface that is curved lengthwise of the heel, and means for shifting the stroke of the tool, as the heel moves past the tool, so that the stroke terminates always on a line between the attaching face of the heel and the surface of the shank at the breast line.

21. A heel-breasting machine comprising a reciprocating tool arranged to cut heightwise of the heel from tread surface to attaching face at the breast line and progressively across the heel from one side to the other, means for supporting a shoe for widthwise movement relative to

the tool for feeding its heel past the tool to breast the heel, said supporting means being arranged continuously to move the heel past the tool, means for shifting the tool lengthwise of the heel during the breasting operation to cause the tool to cut a breast surface that is curved lengthwise of the heel, and means for shifting the tool laterally of its stroke to cause the tool to follow the moving heel during its cutting action thereon.

22. A heel-breasting machine comprising a reciprocating tool arranged to cut heightwise of an attached heel from tread surface to attaching face at the breast line and progressively across the heel from one side to the other, means for supporting a shoe for widthwise movement relative to the tool for feeding its heel past the tool to breast the heel, said supporting means being arranged continuously to move the heel past the tool, guide means for the tool, means for moving the guide means to shift the tool lengthwise of the heel during the breasting operation for causing the tool to cut a breast surface that is curved lengthwise of the heel, and means for moving the guide means widthwise of the heel to shift the tool laterally of its stroke for causing the tool to follow the moving heel during its cutting action thereon.

23. A heel-breasting machine comprising a reciprocating tool arranged to cut heightwise of an attached heel from tread surface to attaching face at the breast line and progressively across the heel from one side to the other, means for supporting a shoe for widthwise movement relative to the heel for feeding its heel past the tool to breast the heel, said supporting means being arranged continuously to move the heel past the tool, means for shifting the tool lengthwise of the heel during the breasting operation to cause the tool to cut a breast surface that is curved lengthwise of the heel, means for shifting the stroke of the tool, as the heel moves past the tool, so that the stroke terminates always on a line between the attaching face of the heel and the surface of the shank at the breast line, and means for moving the tool widthwise of the shoe and laterally of its stroke for causing the tool to follow the moving heel during its cutting action thereon.

24. A heel-breasting machine comprising a reciprocating tool arranged to cut heightwise of an attached heel from tread surface to attaching face at the breast line and progressively across the heel from one side to the other, means for supporting a shoe for widthwise movement relative to the tool for feeding its heel past the tool to breast the heel, said means being arranged continuously to move the heel past the tool, guide means for the tool, means for shifting the stroke of the tool, as the heel moves past the tool, so that the stroke terminates always on a line between the attaching face of the heel and the surface of the shank at the breast line, means for moving the guide means to shift the tool lengthwise of the heel during the breasting operation for causing the tool to cut a breast surface that is curved lengthwise of the heel, and means for moving the guide means widthwise of the heel to shift the tool laterally of its stroke for causing the tool to follow the moving heel during its cutting action thereon.

25. A heel-breasting machine comprising a tool for cutting heightwise of an attached heel and progressively across the heel from one side to the other, and shoe-supporting means for moving a

shoe to feed its heel past the tool for breasting the heel, said means being arranged to move the shoe at a relatively rapid rate from a loading position remote from the tool to a working position adjacent to the tool, then to move the shoe slowly to feed the heel past the tool during the breasting operation, and finally to return the shoe to the loading position at said rapid rate.

26. A heel-breasting machine comprising a reciprocating tool for cutting heightwise of an attached heel, means for supporting lasted shoes for movement to feed their heels past the tool, while it is operating, to cause the tool to breast the heels progressively from one side to the other, said supporting means comprising a revolvable turret with a plurality of shoe-supporting jacks thereon, and means for revolving the turret to transfer said jacks successively from a loading position remote from the tool to a working position beneath the tool.

27. A heel-breasting machine comprising a reciprocating tool for cutting heightwise of an attached heel and progressively across the heel from one side to the other, means for supporting lasted shoes for movement to feed their heels past the tool to breast the heels, said means comprising a revolvable turret having a plurality of shoe-supporting jacks thereon, and means under the control of an operator for revolving the turret at fast and slow speeds to transfer said jacks successively from a loading position remote from the tool to a working position adjacent to the tool, and to move the jacks slowly as a heel is being fed past the tool.

28. A heel-breasting machine comprising a reciprocating tool for cutting heightwise of an attached heel and progressively across the heel from one side to another, means for supporting lasted shoes for movement to feed their heels past the tools to breast the heels, said means comprising a revolvable turret having a plurality of shoe-supporting jacks thereon, and means under the control of an operator for revolving the turret at fast and slow speeds quickly to transfer the jack successively from a loading position remote from the tool to a working position adjacent to the tool, slowly to move the jacks in loading position to permit removal and loading of shoes and in working position to feed heels past the tool during breasting operations, and quickly to return the jacks to loading position.

29. A heel-breasting machine comprising a reciprocating tool for cutting heightwise of an attached heel and progressively across the heel from one side to the other, means for supporting lasted shoes for movement to feed their heels past the tool to breast the heels, said means comprising two shoe-supporting jacks arranged for movement from a loading position remote from the tool to a working position adjacent to the tool, and means for quickly moving said jacks between said positions and for slowly moving said jacks when in said positions and during breasting and loading operations.

30. A heel-breasting machine comprising a reciprocating tool for cutting heightwise of an attached heel and progressively across the heel from one side to the other, means for supporting lasted shoes for movement to feed their heels past the tool to breast the heels, said means comprising two supporting jacks arranged for movement in a circular path from a loading position remote from the tool to a working position adjacent to the tool, and means for successively moving each of said jacks quickly from loading

position to working position, slowly through the working position, quickly from working position to loading position, and slowly through the loading position.

31. In a heel-breasting machine, a tool for breeding attached heels progressively from one side to the other, means for supporting lasted shoes for movement to feed their heels past the tool to breast the heels, said means comprising a revolvable turret having shoe-supporting jacks thereon, means for revolving the turret to transfer the jacks successively from a loading position remote from the tool to a working position adjacent to the tool, and means associated with the turret for rotating the jacks on the turret as the turret revolves so that shoes on said jacks are maintained in the same orientation, with their heels toward the tool and their foreparts toward the front of the machine, in both said loading and said working positions.

32. A heel-breasting machine comprising a reciprocating breeding tool for breeding attached heels progressively from one side to the other and means for supporting lasted shoes for movement to present them to the tool, said means comprising a revolvable turret having shoe-supporting jacks thereon, means for revolving the turret to transfer the jacks successively from a loading position remote from the tool to a working position adjacent to the tool, and means associated with the turret for rotating the jacks on the turret as the turret revolves so that shoes on said jacks are maintained in the same orientation, with their heel ends toward the tool and their foreparts toward the front of the machine, in both said loading and said working positions.

33. In a heel-breasting machine having a reciprocating breeding tool for breeding attached heels progressively from one side to the other and a revolvable turret, a jack on the turret for supporting a shoe for movement to feed its heel past the tool as the turret rotates, means for revolving the turret to transfer said jack between a loading position remote from the tool to a working position adjacent to the tool, and cam means associated with the turret and jack for rotating the jack as the turret revolves so that a shoe may be loaded onto said jack when the jack is in loading position with its heel end away from the operator and presented to the tool in the same relative position on the jack.

34. In a heel-breasting machine having a tool for operating on an attached heel, a shoe-supporting jack for holding a lasted shoe during the action of the tool on its heel comprising a last-engaging abutment, a cooperating heel-clamping member, forepart-supporting means arranged yieldably to support the forepart of a lasted shoe while it is being leveled on the jack, and means for locking the forepart-supporting means when the heel-clamping member is operated to clamp the shoe in the jack.

35. In a shoe machine having a tool for operating on a shoe, a shoe-supporting jack comprising a last-engaging abutment, a cooperating heel-clamping member, forepart-supporting means arranged yieldably to support the forepart of a lasted shoe while it is being leveled on the jack, and means for locking the forepart-supporting means when the heel-clamping member is operated to clamp the shoe in the jack.

36. In a heel-breasting machine having a tool for operating on an attached heel, a shoe-supporting jack for holding a lasted shoe during the action of the tool on its heel, said jack comprising

ing a last-engaging abutment for supporting the heel end of a lasted shoe, a heel-clamping member arranged for movement against the lift surface of the heel of a shoe supported on said abutment for clamping the shoe in the jack, forepart-supporting means yieldable to permit leveling of the shoe prior to the operation of the clamping member, locking means for said forepart-supporting means, and means for moving the clamping member into clamping engagement with the heel and for operating the locking means to clamp the shoe in the jack and to provide a rigid support for the forepart of the shoe.

37. In a shoe machine having a tool for operating on the heel of a shoe, a shoe-supporting jack comprising a last-engaging abutment for supporting the heel of a lasted shoe, a heel-clamping member arranged for movement against the lift surface of the heel of a shoe supported on said abutment for clamping the shoe in the jack, forepart-supporting means yieldable to permit leveling of the shoe prior to the operation of the clamping member, locking means for said forepart-supporting means, and means for moving the clamping member into clamping engagement with the heel and for operating the locking means to clamp the shoe in the jack and to provide a rigid support for the forepart of the shoe.

38. In a shoe machine having a tool for operating on the heel of a shoe, a shoe-supporting jack comprising a heel-clamping plate arranged for movement against the lift surface of the heel of a shoe, a last-supporting abutment mounted for movement from a loading position clear of the clamping member to an operative position to bring the heel of a shoe supported thereon beneath the clamping plate, forepart-supporting means associated with the abutment and movable from a loading to a supporting position, connections between the abutment and the forepart-supporting means for moving the abutment to its operative position when the forepart-supporting means is moved to its supporting position said forepart-supporting means being yieldable to permit leveling of the shoe after said movements, and means for moving the clamping means into clamping engagement with the heel of the shoe and for locking the forepart-supporting means.

39. In a shoe machine having a tool for operating on the heel of a shoe, a shoe-supporting jack comprising a heel-clamping plate arranged for movement against the lift surface of the heel of a shoe, a last-supporting abutment mounted for movement from a loading position clear of the clamping member to an operative position to bring the heel of a shoe supported thereon beneath the clamping plate, forepart-supporting means associated with the abutment and movable from a loading to a supporting position, connections between the abutment and the forepart-supporting means for moving the abutment to its operative position when the forepart-supporting means is moved to its supporting position, and means for moving the clamping means into clamping engagement with the heel of the shoe, said connections including a toggle which is straightened during movement of the forepart-supporting means to supporting position and a link between the toggle and the last-supporting abutment, the toggle being operative, when so straightened, rigidly to hold the forepart-supporting means against displacement and

the link being operative to hold the toggle straightened when the clamping member is clamped against the heel of a shoe supported on the abutment.

40. In a shoe machine having a reciprocating breasting tool for operating on the heel of a shoe, a shoe-supporting jack comprising a heel-clamping plate arranged for movement against the lift surface of the heel of a shoe, a last-supporting abutment mounted for movement from a loading position clear of the clamping member to an operative position to bring the heel of a shoe supported thereon beneath the clamping plate, forepart-supporting means associated with the abutment and movable from a loading to a supporting position, connections between the abutment and the forepart-supporting means for moving the abutment to its operative position when the forepart-supporting means is moved to its supporting position, said forepart-supporting means being yieldable to permit leveling of the shoe after said movements, and means for moving the clamping means into clamping engagement with the heel of the shoe and for locking the forepart-supporting means, said connections including a toggle which is straightened during movement of the forepart-supporting means to supporting position and a link between the toggle and the last-supporting abutment, the toggle being operative, when so straightened, rigidly to hold the forepart-supporting means against displacement and the link being operative to hold the toggle straightened when the clamping member is clamped against the heel of a shoe supported on the abutment.

41. In a heel-breasting machine having a reciprocating breasting tool for operating progressively across an attached heel from one side to the other, a shoe-supporting jack for holding a lasted shoe and for moving the heel of the shoe past the tool to breast the heel, said jack comprising a manually operated heel-clamping member for clamping the shoe in the jack during the action of the tool to breast the heel, and means for automatically releasing the shoe from the clamping member after completion of the breasting operation.

42. A shoe machine comprising a tool for operating on a shoe and a shoe-supporting jack for holding and moving a shoe to present it to said tool, said jack comprising a manually operated heel-clamping member for clamping the shoe in the jack during the action of said tool, means operated by movement of the jack for exerting additional clamping pressure prior to the action of the tool, means for locking the heel-clamping member during the action of the tool, and means for automatically releasing the member to free the shoe after the completion of the action of said tool.

43. In a heel-breasting machine having a tool for operating progressively across an attached heel from one side to the other, a movable shoe-supporting jack for holding a lasted shoe and for moving the heel of the shoe past the tool to breast the heel, said jack comprising a heel-clamping member, manual means for initially clamping said member against the heel of a shoe in the jack, means operated by movement of the jack for exerting additional clamping pressure

on the member prior to the action of the tool on the heel, means for locking the member during the action of the tool, and means for automatically releasing the member to free the heel after the completion of the breasting operation.

44. In a heel-breasting machine having a tool for operating progressively across an attached heel from one side to the other, a movable shoe-supporting jack for holding a lasted shoe and for moving the heel of the shoe past the tool to breast the heel, said jack comprising a heel-clamping member, forepart-supporting means yieldable to permit leveling of the shoe prior to the operation of the heel-clamping member, means for moving the heel-clamping member into heel-clamping position and at the same time locking the forepart-supporting means, means for holding the clamping member in clamping position during the action of the tool on the heel, and means for releasing the clamping member to free the heel and unlock the forepart-supporting means after the completion of the breasting operation.

45. In a heel-breasting machine having a tool for operating progressively across an attached heel from one side to the other, said tool being arranged for movement transversely of the direction of relative feeding movement between the tool and a heel during breasting to cut a breast surface that is curved lengthwise of the heel, means for supporting and moving a lasted shoe to feed its heel past the tool to breast the heel, said means comprising a jack having a heel-clamping member provided with cam means for effecting said movement of the tool during the feeding of a heel past the tool, said clamping member being detachably and adjustably mounted on the jack so that it may be replaced by other clamping members having cam means adapted to cause the tool to cut breast surfaces of different curvatures and adjusted on the jack to vary the amount of material removed by the tool during the breasting operation.

46. A heel-breasting machine comprising a frame, a reciprocating breasting tool arranged to cut heightwise of an attached heel and progressively, with a series of cuts, across the heel from one side to the other, means for supporting a shoe to present its heel to the tool, while it is operating, for breasting the heel, said means comprising a jack movable to feed the heel of a shoe supported thereon past the tool, and means on the frame for engaging and stabilizing the jack during the action of the tool on the heel.

47. A heel-breasting machine comprising a frame, a reciprocating breasting tool arranged to cut heightwise of an attached heel and progressively, with a series of cuts, across the heel from one side to the other, means for supporting shoes to present their heels to the tool, while it is operating, for breasting the heels, said means comprising a plurality of jacks movable to feed the heels of shoes supported thereon successively past the tool, and means on the frame for engaging and stabilizing each jack during the action of the tool on the heel of the shoe supported thereby.

CERTIFICATE OF CORRECTION.

Patent No. 2,310,301.

February 9, 1943.

BERNARD T. LEVEQUE.

It is hereby certified that error appears in the printed specification of the above numbered patent requiring correction as follows: Page 9, second column, line 29, for "breat" read --breast--; page 10, first column, line 66, for "breasts" read --breast--; page 12, first column, lines 5-6, strike out "reciprocating breasting"; and that the said Letters Patent should be read with this correction therein that the same may conform to the record of the case in the Patent Office.

Signed and sealed this 27th day of April, A. D. 1943.

(Seal)

Henry Van Arsdale,
Acting Commissioner of Patents.
